DESIGN FOR A CASING FOR GAS SUPPLYING APPARATUS

Gerald D. Peet, Montclair, N. J., assignor to
Wallace & Tiernan Company, Inc., Belleville,
N. J., a corporation of New York

Application September 1, 1934, Serial No. 53,138

Term of patent 14 years

To all whom it may concern:

Be it known that I, GERALD D. PEET, a citizen of the United States, residing at Montclair, in the county of Essex and State of New Jersey, have invented a new, original and ornamental Design for a Casing for Gas Supplying Apparatus, of which the following is a specification, reference being had to the accompanying drawing, forming part thereof.

The drawing shows in perspective view a casing for gas supplying apparatus embodying my invention.

I claim:

The ornamental design for a casing for gas supplying apparatus, substantially as shown.

In witness whereof, I have hereunto set my hand,

GERALD D. PEET.
